UNITED STATES PATENT OFFICE

CESARE BARRIERI, OF NEW YORK, N. Y., ASSIGNOR TO VORTEX CUP COMPANY, OF CHICAGO, ILLINOIS, A CORPORATION OF DELAWARE

CUP DISPENSER

Application filed December 14, 1929. Serial No. 413,960.

This invention relates to dispensers designed particularly for dispensing unflanged flexible conical drinking cups.

One of the important objects of the invention is to produce a dispenser which is of the ordinary capacity but which is exceedingly light, and, therefore, particularly desirable and advantageous in the aviation field for use on aircraft where lightness is a very essential factor.

A further important object is to produce such light weight dispenser by having the parts thereof in the form of castings, die products, or tubing of some light material, such as aluminum, or by forming up the parts from light sheet metal, such as tin plate.

A further object is to have the cup supporting, dispensing and escapement teeth formed integral with one of the dispenser parts, preferably by deflection from the sides thereof.

A still further object is to reduce the number of parts to a minimum and to make their manufacture and production simple and economical, in order to produce an efficient dispenser which can be sold for a very reasonable price, as for example, for household use.

The above enumerated and other important features of my invention are incorporated in the structure disclosed in the drawings, in which:

Figure 1 is a front elevation of one form of dispenser embodying features of my invention;

Figure 2 is an enlarged diametrical section on plane II—II of Figure 1;

Figure 3 is a section on plane III—III of Figure 2;

Figure 4 is a front elevation of another form of dispenser;

Figure 5 is an enlarged diametrical section on plane V—V of Figure 4;

Figure 6 is a section on plane VI—VI of Figure 5;

Figure 7 is a plan view of a conical cup supporting base showing the manner in which cups are withdrawn from the dispensing teeth;

Figure 8 is a section on plane VIII—VIII of Figure 7; and

Figure 9 is a plan view of a modified form of cup supporting base.

The form of dispenser illustrated in Figures 1 to 3 comprises a stack supporting and cup dispensing base 10 having upper and lower circumferential rows or zones of supporting and dispensing teeth 11 and 12 respectively. This base may be an ordinary casting, or a die casting, or may be a length of tubing with the teeth deflected therefrom, and preferably a light metal, such as aluminum, is used. When formed of a length of tubing, the upper teeth 11 are deflected therefrom to extend radially inwardly and are preferably regularly spaced apart circumferentially. Such deflection of the teeth leaves the openings 13, and the teeth at their inner ends are preferably rounded horizontally, as clearly shown in Figure 3. The lower end of the tube is primarily cut to leave the teeth 12 and then the lower end of the tube with the teeth thereon is deflected radially inwardly, so that the teeth 12 extend radially, and the inner ends of these teeth are also preferably rounded horizontally and may, as shown, be spaced to be in vertical alignment with the respective teeth 11, or the teeth 11 and 12 may be relatively staggered or circumferentially offset. The upper teeth 11 are preferably a distance below the upper edge of the base.

Spanning the base is a yoke 14 which at its ends receives the diagonally opposite trunnion studs 14 and 16 extending radially from the base and bearing nuts 17 and 18 outside of the yoke legs for adjusting the frictional engagement of the base with the yoke. Extending upwardly from the back of the yoke is a bracket 19 having holes 20 by means of which it may be secured to a suitable support. The upper end 21 of the bracket extends forwardly and terminates in a slot 22 above the axis of the base 10.

The enclosing cover or container for the stack of cups supported upon the upper dispensing teeth 11 is in the form of a cylindrical shell, which may be a length of tubing preferably of a light metal such as aluminum.

The container is secured at its lower end in a ferrule 24 which may be a casting or a short length of tubing. This ferrule fits into the base above the teeth 11 and has the annular 5 overhanging shoulder 25 for engaging with the upper edge of the base to thus seat the container on the base in axial alignment therewith. The upper end of the container is closed by a cover 26 which has a lug 27 extending upwardly therefrom and adapted to enter the slot 22 to be thereby guided into accurate position relative to the bracket 19. A flat spring 28 is secured at its rear end on the extension 21 of the bracket and above the slot 10 22 has a hole 29 for receiving the bead or nub 30 on top of the lug 27 in order to yieldably lock the cup container in vertical position on the bracket. The front end 31 of the spring is rounded to facilitate engagement 15 thereof by the fingers. The container structure, together with base, can thus be tilted forwardly after the spring has been raised to release the nub 30 and then the cover 23 can be removed from the base to receive a 20 fresh charge of cups. After loading, the container structure is swung rearwardly and the lug 27, by engaging in the slot 22, will guide such movement, and, when the nub 30 reaches the hole 29, the spring will drop against the 25 bracket stop 21 and will lock the container structure in proper vertical dispensing position. A section is preferably punched out of the lower end of the bracket 19 to form a stop abutment 32 to be engaged by the base 30 when the structure is swung forwardly, in order to limit such forward swing. A bezel frame 33 may be applied to the front of the cover 23 over an opening 34 and supports a pane of glass 35 or other transparent 35 material through which it may be readily ascertained when the device requires replenishing with cups. The escapement and dispensing operation of the cups will be referred to hereinafter.

40 In the modified form of dispenser illustrated in the Figures 4, 5, and 6, a single cylindrical shell 36 provides for supporting and enclosing the cups. The shell may be formed from a rectangular piece of light sheet metal, such as tin plate, from which the upper teeth 37 and the lower end teeth 38 have been deflected, the plate being then bent into cylindrical form with its edges secured together as by seaming indicated at 39, 45 with the upper and lower teeth then extending radially inwardly. The upper end of the container is provided with a detachable cover 40 having a knob 41, and this cover can be readily removed for the insertion of a stack 50 of conical cups. A T-shaped bracket or supporting frame 42 preferably of sheet metal, is secured to the container, its upper laterally extending arms having screw or nail holes 43 at their outer ends and the vertical leg of 55 the frame having a screw or nail hole 44 at

its lower end, so that the device may be readily secured to a supporting wall.

The dispenser disclosed in Figures 1 to 3, inclusive, being of aluminum and, therefore, very strong, substantial and very light, is particularly fitted and desirable for installation on aircraft, where lightness is a very essential factor. The form of dispenser disclosed in Figures 4, 5, and 6 is also very light, yet substantial, and can be economically manufactured to be sold at a very reasonable price for household or other uses, where the more expensive types of dispensers are not desired.

Figures 7 and 8 show a supporting base 45 in the form of a sheet metal cylindrical ring or annulus having upper and lower escapement and dispensing teeth 46 and 47 deflected radially inwardly therefrom. The base may be formed from a length of sheet metal tubing or from a flat sheet metal blank 80 rolled to circular form, and, instead of providing a supporting bracket as shown in Figures 2 and 5, a short bracket is secured to the side of the base with radially extending flanges 49 and 50 at its ends. To support the base on a wall, a U-shaped bracket or socket member 51 is provided whose ends 52 and 53 are deflected to receive between them the flanges 49 and 50 of the bracket 48 on the base, the base flanges being slid downwardly 85 between the wall bracket flanges. In order to limit the applying movement and afford a positive seat for the base, lateral wings 54 and 55 are provided at the upper ends of the flanges 49 and 50, which wings extend across 90 and against the top of the wall bracket flanges 52 and 53, to thus securely seat the base. The bracket 48 may be brazed or welded to the base ring, and, when the base ring is rolled from a flat piece of sheet metal, the bracket 100 can be secured across the ends of the rings and form a tie plate therefor.

In Figure 9 a modified arrangement is shown, the base 56 being rolled up from a sheet metal plate into substantially circular 110 form, with its end sections 57 and 58 extended radially to be slid vertically into socket engagement with a wall bracket 59, the wings 60 and 61 being formed at the upper end of the flanges 57 and 58 to seat against the top 115 of the wall bracket flanges. The base has upper and lower circumferential rows of dispensing teeth 62 and 63 deflected therefrom.

In Figures 7 and 8, I show the manner in which a stack of conical cups is supported 120 on the upper row or zone of dispensing teeth, and the manner in which the lowermost cup is withdrawn and dispensed from the stack. The figures of the upper zone project into the path of the stack and engage with the lowermost cup a short distance below its upper edge whereby to support the stack. The teeth or fingers are rigid and unyielding, so that, when the lowermost cup is pulled downwardly, its conical wall will be deflected in- 125 130

wardly by the teeth and will bulge outwardly into the spaces between the teeth, as illustrated in Figure 7, such deflection and bulging easing the withdrawal movement of the 5 cup past the teeth and separation thereof from the stack, and, as soon as the lowermost cup has cleared the teeth of the upper zone, these teeth will engage with the next cup and support the stack thereby. A lower zone 10 of teeth is not absolutely essential but is provided as a precautionary measure in case one or more cups should follow the lowermost cup which is being pulled downwardly. Should any such cups follow, they will be 15 retained by the lower zone of teeth, as the lowermost cup is finally withdrawn. The distance of the upper zone of teeth above the lower end of the base is such that the lowermost cup will extend a sufficient distance beyond the lower end to be readily 20 grasped for withdrawal.

It is evident that on the base structures disclosed in Figures 7, 8, and 9, a container or closure member may be provided for the 25 stack above the base. Such closure structure could be like that disclosed in Figure 2, or the closure could form a continuation of the base and be integral therewith, as in the structure shown in Figure 5.

30 It is to be understood that, although I have shown and described several practical and efficient embodiments of the features of my invention, the invention is not limited thereto, but only in so far as defined by the scope 35 and terms of the appended claim.

I claim as my invention:

In a cup dispenser, a supporting base for 40 a stack of upright flexible cups, said base being a cylindrical shell formed from a single piece of light sheet metal, a zone of teeth a distance below the upper edge of the base deflected therefrom, and extending radially inwardly, said teeth supporting the stack and controlling the withdrawal therefrom one at 45 a time of the cups, and a second zone of teeth below said upper zone and constituting continuations of the lower edge of said base and deflected so as to extend radially inwardly, said second zone serving to retain and prevent dispensing with the withdrawn cup of 50 any other cup or cups which may have followed the withdrawn cup past the upper zone of teeth.

In testimony whereof I have hereunto 55 subscribed my name at New York, New York County, New York.

CESARE BARBIERI.
